13 Claims. (Cl. 176—122)

The luminescence of gases and vapours has been utilized for the production of light or ultraviolet radiation in electric lamps of various designs. A common and essential feature of all lamps hitherto realized or suggested is, however, that by means of electrodes or by induction, electric fields are produced in a discharge space. This field produces an electric stream of ions and electrons and by this stream the input of the electric field is transformed in the same discharge space, partly in heat and partly in radiation. All discharge lamps such as arc lamps, glow lamps, spark gaps or electrodeless induction lamps of all designs, work on this principle.

This invention relates to a lamp or light source in which the transformation of the electric energy into radiation is performed in a manner employing a different principle. The essential part of the new lamp is a device which shall be called electron beam source, in which the electric input of the lamp is first transformed into kinetic energy of electrons. The velocities of these electrons correspond to the voltage applied to the lamp, which is preferably in the range of 50-300 volts. Beams of these electrons enter a lighting space, containing gases or vapours or a mixture thereof. The total intensity of these electron beams corresponds to the main current flowing through the lamp. Under working conditions the gases and vapours in the lighting space are ionized and form a plasma, an electrically neutral medium, appreciably free from electric fields. The plasma contains positive ions and electrons in very nearly equal concentrations. The latter, which under working conditions have average energies of the order of a few volts shall be called plasma-electrons, to distinguish them from the beam-electrons, or primaries, which have initial energies of 50-300 volts.

It has been discovered that a new process for the transformation of the kinetic energy of the primary electrons comes into action if the intensity of the electron beams and the pressure in the lighting space is properly chosen, resulting in a high lighting efficiency. This process is the transfer of the kinetic energy of the primary electrons to plasma electrons by means of the electrostatic forces acting between these charged particles. The plasma electrons in turn utilize this energy by collision with gas molecules exciting these to radiation. This process has proved more efficient than the direct utilization of the primary energy by collision with molecules. The conditions necessary for the carrying out of the new process are: a high concentration of plasma-elec-

trons, therefore a high primary intensity, and an appropriate choice of the pressure. At too low a pressure the primary electrons strike the walls, without having delivered their energy within the lighting space. At too high a pressure the energy of the primaries is mainly lost by collisions with molecules and the efficiency decreases again.

Thus for instance in a lamp filled with neon and working at 70 volts, the efficiency was 10 lumens per watt at a pressure of 0.4 mm. neon and a current of 0.6 amp. At 0.3 mm. neon and 0.25 amp. the efficiency was only 5 lumens per watt and at 0.6 mm. and 1.2 amps. only 7 lumens per watt.

Although the optimal pressure varies according to the nature of the filling gas or mixture, it can be stated as a rough rule that the pressure is best chosen in such a way that the linear dimensions of the vessel shall be from 5 to 50 times the mean free path of the primaries. This gives for the inert gases helium and neon a few tenths, or argon and the metals of the second column of the periodic system a few hundredths, and for the alkaline metals a few thousandths mm. Hg-pressure.

In the accompanying drawings which illustrate this invention Fig. 1 is a drawing of the lamp, showing only the main parts, 1 being the vessel containing the lighting space, with walls transparent to the radiation desired. In this example the vessel has the form of a pear-shaped bulb containing near its neck the electron source 2, the design of which is explained later. This source emits electron beams of high intensity, starting for example parallel to the lamp axis, but diffusing soon after leaving the source and filling the whole lighting space with a radiating plasma.

The electron beam source in the lamp according to this invention has to emit electron beams with velocities corresponding to 50-300 volts and intensities of several hundred milliamperes or several amperes into a space filled with a highly ionized gas, in a perfectly controlled way. Moreover, the electrons must be produced economically, with as small power consumption as possible.

In the electron beam source according to the invention the strong electron beam required is emitted by one or more electron guns of special design and dimensions by which a perfect control of the beam production is obtained and uncontrollable gas discharges, especially arcing safely avoided.

According to one method of carrying out the invention a large number of small electron-guns are chosen. It has been found that each of the

weak beams which together constitute the primary beam of the lamp can be produced with a positive characteristic, i. e. with a current rising with increased voltage. This may be effected according to this invention, by a prevailing electronic space charge inside the electron guns. Since each unit possesses a positive characteristic, they can safely work in parallel, and the whole source can even be put on the mains without stabilizing elements such as resistances, chokes and the like, as required by ordinary gas discharge devices.

An example of an electron beam source according to this invention is shown in Figs. 2 and 3. This is constructed essentially of conducting and insulating discs piled together so as to form a solid body. The cathode 3 is a disc of metal, e. g. nickel, having formed in it a great number of concave dimples 4, which are distributed according to some regular pattern. These dimples form the cathodes of the electron guns. They are coated with electron-emitting materials of low work function, e. g. baryta. The cathodic body is indirectly heated by a heating body 5, a spirally wound wire, e. g. of tungsten, embedded in the groove between two insulating discs 6 and 7 of refractory ceramic material.

Three discs are placed over the cathode, 8, 9 and 10, all three having corresponding perforations, which together with the dimples in the cathode form the accurately adjusted small electron guns. Of these 8 and 10 are of insulating material, while 9 is conducting and shall be called the accelerating electrode. Disc 10 will be referred to as the plasmafilter, for reasons to be explained below. The whole source is put in a case 11, of metal or preferably of ceramic insulating material, to prevent heat losses. This is fitted with a conducting sleeve 12, representing the anode. This is the electrode through which the current which enters the lighting space in the form of the primary electron beams returns into the system mains. It is almost exclusively carried into the anode by slow plasma electrons. If the anode has a sufficient area there is no anode-drop on it, nor even a negative drop, and the loss is practically negligible.

Fig. 3 is a view of the source from the plasma side, showing the orifices 13 of the electron guns. Fig. 4 is a section of one of the electron guns, on which the working principle can be demonstrated, 14 is the cathode. The concave, that is the oxide coated surface emits electrons which start perpendicularly to it thereby avoiding hitting the accelerating electrode 15. Another important function of the concavity is that it creates an increased negative space charge before the cathode, thus contributing to the current limitation. After passing through the accelerator, the electrons fly across the plasma-filter 16, the most essential part of the device, into the lighting space.

The space 17 between cathode and accelerator will be referred to as the accelerating space. The accelerator may be connected with the anode, in which case the electrons obtain their full velocity within this space. It may however be maintained at a lower potential. This can be realized, for example by connecting the accelerator with the anode across a high resistance or by putting it on a potentiometer. In this case the electrons are further accelerated between 17 and the plasma, reaching the orifice with full velocity.

The plasma-filter 16 of insulating material has the important function of preventing the highly

ionized plasma from intruding into the accelerating space, which would lead to a breakdown of the negative space charge and result in an arc, destroying the cathode or the whole source. This is effected by the filter in the following way: The 5 walls of the filter collect a number of stray electrons and assume a negative charge. By this they repel the rest of the electrons and therefore the beam is concentrated essentially about the axis of the holes, thus creating a negative space 10 charge. By this a field is produced along the axis which accelerates slightly the electrons coming from the cathode and repels the electrons coming from the plasma side. The positive ions on the contrary are drawn inwards, but because 15 of the strong radial field most of them are thrown upon the walls, where they are neutralized. Thus only a slight fraction reaches the accelerating space, insufficient to neutralize the space charge or to disintegrate the cathode. On account of its 20 filtering action on the constituents of the plasma, ions and electrons, the member is given the name of plasma-filter.

The electron and heat losses in the filter can be reduced to a few percent of the whole input 25 by correct dimensioning. The losses are mainly determined by the number of ions formed by the primary beam within the filter, as every positive ion formed attracts one electron to the wall. These losses are also reduced by the circumstance, 30 that the filter holes are heated by the hot cathode, therefore the gas is diluted in them and the mean free path is increased.

An electron gun of the kind described has a 35 positive characteristic which is only a function of the geometrical dimensions and of the gas pressure, but independent of the heating and emissivity of the cathode. Thus the input of such a source can be exactly predetermined and remains constant even if there is an eventual partial 40 wear of the cathode. Beam sources of this kind can be put on the mains of lighting systems with the usual voltages of 110-250 volts.

It has been found, that if the plasmafilter is properly dimensioned, the accelerating electrode 45 and the concavity of the cathode can be dispensed with, thus allowing an important simplification of the whole device. Fig. 5 shows a section of the simplified electron source, which contains only the plane, preferably oxide coated cathode 18 50 and the plasmafilter 19. In this case the electrons are accelerated between cathode and plasma. The action of the negative charge on the walls ensures as described above a positive characteristic. No arcing occurs, which would be 55 inevitable if an oxide coated cathode was exposed directly to a plasma. Such a source will start automatically after heating the cathode and applying the voltage, no special starting device being required.

This device will only work correctly if properly dimensioned, the characteristics being very sensitive to the length and cross dimensions of the holes. For round holes the diameter is the most important dimension, for slits the width. The 65 importance of the diameter is illustrated by the following example: Let the voltage be 100 volts, the filling gas neon, and the pressure 0.25 mm. For obtaining a current of 40 milliamperes out of one hole the following lengths are required: with 70 0.89 mm. diameter, 1.3 mm.; with 0.93 mm., 1.8 mm.; with 0.97 mm., 2.5 mm. Thus a change of 4% in the diameter requires for its compensation a change of about 40% in length.

The importance of the length is shown by the 75

following example: at 100 volts and 0.25 mm. neon a hole of 0.93 mm. diameter yields 40 ma. at 1.8 mm. length, while at 2.3 mm. length it yields only 15 ma.

5 By varying the diameter and the length of the holes within rather narrow limits it is possible to develop sources for every required voltage and current. As we can still choose the number of the holes freely, there is even an infinite variety 10 of sources possible for one given lamp. Experiments have shown that with a filter having small holes it is possible to keep the length down, and by this the losses, and to have at the same time a low current density, thus preventing excessive 15 wear on the cathode. Excessively small holes however require filters too thin to be easily manufactured and require sources which are too big. On the other hand holes of large diameter require small sources, having few holes or even 20 only one hole. As however the current density in this case is high, filters with only one or a few holes are preferably used in conjunction with plasma-cathodes such as are described below. Thus 1.1 mm. can be considered as a practical 25 upper limit for the hole diameter whereas 0.8 mm. is a practical lower limit.

In another construction of the beam source a plasma may be employed as electron source. This plasma can be produced by an auxiliary 30 discharge, preferably an arc. Fig. 6 is a section of such a source. The source contains a cathode 20, which is coated with substances of low work function and is preferably of the type used for 35 arc discharge lamps or rectifiers. The sleeve 21 is the anode of the auxiliary arc. Both cathode and anode of the arc are enclosed in a box 22 of ceramic insulating material. One face of 40 this box is the plasmafilter 23. The sleeve 24 on the outside of the box is the anode, as in the previous patterns.

The auxiliary arc, which is operated at low voltage, (10-25 volts) fills the whole of the inside of the box 22 with its plasma. As soon as the accelerating voltage is applied to the anode 24, 45 electron beams pass through the holes. The characteristics of the filter are but little different from what they were with plane cathodes underneath them. With this device filters are practicable having only a few holes or even only one.

50 Experiments have proved that it is possible to draw almost the whole current of the arc through the holes of the plasmafilter. It is even possible to switch off the anode 21 after having started the electron beams, the whole current flowing now 55 from the cathode 20 to the filter through the plasma corresponding to the negative glow in arcs. The current flows in the form of space charge limited electron beams through the filter 23 i. e. in a way that is essentially different from 60 the electricity transport obtaining in all known gaseous discharge devices. The current returns to the mains through 24 in the form of slow plasma-electrons.

It is however possible to start the phenomenon 65 described not by an arc but by a glow. For this purpose the auxiliary anode 21 is connected with the positive main across a resistance, too high to allow an arc.

In a further development of this invention, the 70 heating of the cathode may be dispensed with, by using a special type of cathode. It is known that on certain cathode materials, which generally have low heat conductivity with a high power for electron emission, arcs can be struck on cold 75 cathodes. Fig. 7 illustrates an electron source

fitted with a cathode 25 of this kind. A faint glow is started by means of the auxiliary electrode 26, connected across the high resistance 27 to the positive main. The electron beams start instantaneously from the holes of the filter 28 5 and in a very short time the current increases to its final intensity. For lamps of this kind, the current must not be less than a certain minimum of the order of 1 ampere to secure the self-maintenance of the cathode spot. 29 is the anode. 10 Although the phenomena at the cathode are in this case the same as in an arc, the production of the electron beams by the plasmafilter occurs in essentially the same way. Therefore the current-voltage characteristic is very nearly the same 15 as for the arrangement shown in Fig. 5, the only difference being, that a few volts are added to the voltage for supplying the cathode drop and the heating of the cathode.

Beam sources with plasma electron sources 20 have the great advantage that filters of any shape can be used, the plasma fitting exactly to any surface. Thus for example, a convergent bundle of beams can be produced as shown in Fig. 8. Here the plasmafilter 30 is spherically 25 bent and emits electron beams converging in one point 0. This point is surrounded by a nearly globularly shaped very intense glow. In certain gases and vapours such as helium, mercury and cadmium the colour emitted by this concentrated 30 glow has a different colour from and a higher efficiency than the more diffuse glow surrounding it. In other gases as e. g. neon and sodium the efficiency decreases at too high current densities. With such gases a divergent bundle 35 may be used advantageously, as shown in Fig. 9, where the plasmafilter 31 has a convex shape.

An advantage common to the lamps with plasma-source as compared with the other constructions is that the number of fast positive ions 40 striking the cathode can be reduced to almost zero. Thus the cathodes in these sources are working under the same conditions as in low voltage arc lamps permitting of very long lives. Another very important feature of these sources 45 is that cathodes of the self-heating type can be employed, which strike immediately after switching in the lamp. Thus in lamps with permanent gases the lamp gives full light intensity from the start. In lamps which also contain metal vapours, the intensity rises further and reaches its final value after a few minutes. It has been found, however, that already the initial efficiency can equal the efficiency of incandescent lamps if neon is used as a starting gas. Neon 55 gives in the new lamps a soft orange-yellow colour, less glaringly red than in neon discharge tubes.

Theory and experiments have shown that for 60 higher voltages, such as 220-250 volts a better efficiency can be obtained for a given input if two lamps of half this input and half the voltage are connected in series, than if the whole input is consumed in one lamp. Fig. 10 shows how 65 two lamps can be connected in series in one bulb, using a common electron source. In Fig. 10 the essential parts are:—The cathode 32 and the plasma filter 33. The bulb is divided into two parts by means of a diaphragm 34, a central hole 70 in which is covered by a second plasma-filter 35, of the same dimensions as 33. The anode 36 is flush with the diaphragm and its lead 37 is insulated. Here the plasma of the first chamber 75 serves as electron source to the second cham-

ber 39. The two equal plasmafilters 33 and 35 divide the voltage in two equal halves.

So far only direct current constructions have been described. Constructions suitable for alternating current lamps may be made by doubling the essential parts. Fig. 11 shows an alternating current electron beam source, corresponding in design to the direct current source illustrated in Fig. 5. 40 is the heating body of refractory ceramic material. This body is fitted with a spiral groove containing the heating coil 41, which is connected with the system mains parallel to the main lamp circuit. The heating body is fitted with two metallic sheets 42 and 43, which constitute the two cathodes. Instead of sheets a metallic coating such as nickel may be used, for the same purpose. The cathodes are coated with electron-emitting material, such as baryta. The cathodes are covered by the plasmafilter 44 and all parts are enclosed by the ceramic case 45. This is fitted on the outside with two sheets 46 and 47, constituting the anodes. These can be also metallic coatings or preferably carbonized parts of the surface. The latter is more advantageous, as in alternating current lamps the anodes have the potential of the cathode in every second half-period and sputtering as well as the danger of arcing is reduced by carbonizing. The whole source is held together by a rivet 48.

Fig. 12 illustrates a plan view of the source with the plasma-filler removed, showing exposed the cathodes 42 and 43 on the heating body 40. 46 and 47 are the two anodes.

It is also possible in the case of alternating current to dispense with the outer anodes and use the cathodes alternatively as anodes and cathodes. To avoid however a potential drop between the momentary anode and the plasma, which would result in halving the voltage and the input, the number of the holes working as anodes must be chosen greater than the number of holes working as cathodes, e. g. only a part of the holes must be coated with electron emitting material. It is still better to give the anode-holes greater diameters than the cathode-holes. The advantage of this arrangement is, besides its simplicity, that the sputtered material penetrates very slowly in the lighting space and that the anode loss is utilized in heating the cathodes.

Figs. 13 and 14 show a section and plan respectively of an alternating current beam source with a plasma as electron source. The case 48 is divided in two sections. Each cathode 49 and 50 is fitted with a shield 51, 52 opposite the holes of larger diameter 54 of the plasmafilter 53. The electron beams pass through the smaller holes 55. Each section of the case contains striking electrodes 56, 57, connected with the mains across high resistances 58, 59. In Fig. 14 a part of the plasmafilter has been removed.

Fig. 15 is another pattern of the electron beam source according to the invention for alternating current. In this construction the electron beams start through slits radially in all horizontal directions. 60 and 61 are the two cathodes, both heated by the heating body 62 which is connected immediately with the mains. 63 is a flat disc. 64 and 65 two cups, all three of refractory ceramic material which constitute together the case of the beam source, leaving appropriately adjusted slits 66 and 67 on both sides of 63 for the passage of the electron beams. The current returns from the plasma through holes 68 to the anodes 69, which are shaped as flares preferably of one

piece with the cathodes. 70 and 71 are the two striking electrodes, connected with the opposite cathodes by means of high resistances 72, 73 which can easily be manufactured in the form of thin strips of coating with graphite or some other suitable material on the insulating disc 4.

Fig. 16 illustrates a complete lamp made according to this invention; the bulb 74 has an approximately spherical shape. The electron beam source 75 projects a little from the neck 76, which can be long in the case of permanent gases but must be kept short if metal vapours are employed, to avoid condensation of the metals on cold spots. The seals are preferably beads, sealed in the neck. The lamp may be fitted with a screw socket 77 or with any other standard lamp socket. Such a lamp may be secured in any lampholder instead of an incandescent lamp and be operated immediately on the mains of lighting systems with the usual voltage of 100-250 20 volts. The current required by the new lamp is of the order of magnitude of the currents of incandescent lamps. Units of any usual or convenient size can be manufactured.

All gases and vapours can be used in the lamp according to the invention. The efficiency obtained with these equals the best efficiencies obtained in gas discharge lamps, and even surpasses it in many cases. A particular advantage of the new lamp is, however, that a mixed light can be obtained by using two or more different filling gases or vapours, which do not emit light simultaneously in the known gaseous discharge lamps. Thus for instance it is possible in the new lamp to have a simultaneous strong emission of neon and sodium, while in sodium discharge tubes containing neon hitherto made the light emission of neon is almost totally suppressed by sodium.

For general lighting purposes white light is generally required and this has not yet been realized in a satisfactory way in any gas discharge lamp. In the new lamp, however, it is possible to obtain a white light of good quality by mixing neon with mercury vapour. A still better quality with a high efficiency, surpassing considerably the efficiency of incandescent lamps, has been obtained by a mixture of neon, sodium and cadmium. In this mixture the neon yields the best part of the red and a smaller part of the green, while cadmium yields the blue and violet and a part of the green and red and sodium contributes the yellow line.

Thus the new light source possesses a number of advantages, hitherto only obtained with incandescent lamps, but not with gas discharge lamps, such as: white light, broad range of rating, operating on the usual lighting systems without special auxiliary devices as transformers, chokes or the like, automatic starting after switching in, and a handy form, suitable for mass production. In addition, however, it has advantages peculiar to luminescent gases or vapours, that is a broad range of colours and high lighting efficiency.

I claim:

1. An electric lamp comprising an envelope enclosing a lighting space containing rarified gases, an anode, an electron beam source which in turn comprises a hot cathode and a body or plasmafilter provided with openings for the passage of the electron beams, said body or plasmafilter separating the cathode from the lighting space and from the anode, and having insulating material on its surface exposed to the electron beams and to the lighting space, the openings having lateral 75

dimensions so restricted that the voltage-current characteristic of the lamp is positive and independent of excess electron emission by said cathode.

5 2. An electric lamp for use on alternating current comprising an envelope enclosing a lighting space containing rarified gases two anodes an electron beam source for emitting electron beams in both half cycles of said alternating current 10 which in turn comprises two hot cathodes and a plurality of bodies or plasmafilters provided with openings for the passage of the electron beams said bodies or plasmafilters separating the cathodes from the lighting space and from the 15 anodes and having insulating material on their surfaces exposed to the electron beams and to the lighting space the openings having lateral dimensions so restricted that the voltage-current characteristic of the lamp is positive and independent of excess electron emission by said cathodes.

20 3. An electric lamp comprising an envelope enclosing a lighting space containing rarified gases, an anode, an electron beam source which in turn comprises a hot cathode and a body or plasmafilter provided with openings for the passage of the electron beams, said body or plasmafilter separating the cathode from the lighting space and from the anode, and having insulating material 25 on its surface exposed to the electron beams and to the lighting space, the openings having lateral dimensions so restricted that the voltage-current characteristic of the lamp is positive and independent of excess electron emission by said cathode, the depth of any one of said openings being 30 not more than three times the smallest lateral dimension thereof.

35 4. An electric lamp for use on alternating current comprising an envelope enclosing a lighting 40 space containing rarified gases, two anodes, an electron beam source for emitting electron beams in both half cycles of said alternating current, which in turn comprises two hot cathodes and a plurality of bodies or plasmafilters provided with 45 openings for the passage of the electron beams, said bodies or plasmafilters separating the cathodes from the lighting space and from the anodes, and having insulating material on their surfaces exposed to the electron beams and to the lighting 50 space, the openings having lateral dimensions so restricted that the voltage-current characteristic of the lamp is positive and independent of excess electron emission by said cathodes, the depth of any one of said openings being not more than 55 three times the smallest lateral dimension thereof.

5. An electric lamp comprising an envelope enclosing a lighting space containing rarified gases, an anode, an electron beam source which in turn comprises a hot cathode and a body or plasmafilter provided with openings for the passage of the electron beams, said body or plasmafilter separating the cathode from the lighting space and from the anode, said cathode backing 60 said body or plasmafilter, said body or plasmafilter having insulating material on its surface exposed to the electron beams and to the lighting space, the openings having lateral dimensions so restricted that the voltage-current characteristic of the lamp is positive and independent of excess electron emission by said cathode.

6. An electric lamp for use on alternating current comprising an envelope enclosing a lighting space containing rarified gases, two anodes, an electron beam source for emitting electron beams 65

in both half-cycles of said alternating current, which in turn comprises two hot cathodes and a plurality of bodies or plasmafilters provided with openings for the passage of the electron beams, said bodies or plasmafilters separating the cathodes from the lighting space and from the anodes, said cathodes backing said bodies or plasmafilters, said bodies or plasmafilters having insulating material on their surfaces exposed to the electron beams and to the lighting space, the 10 openings having lateral dimensions so restricted that the voltage-current characteristic of the lamp is positive and independent of excess electron emission by said cathodes.

15 7. An electric lamp comprising an envelope enclosing a lighting space containing rarified gases, an anode, an electron beam source which in turn comprises a hot cathode enclosed in a case and communicating with the lighting space and the anode only through openings provided in a body 20 or plasmafilter, said cathode being separated from the body or plasmafilter by a distance exceeding substantially the length of the mean free path through the gases, said body or plasmafilter having insulating material on its surface exposed 25 to the electron beams and to the lighting space, the openings having lateral dimensions so restricted that the voltage-current characteristic of the lamp is positive and independent of excess electron emission by said cathode.

30 8. An electric lamp for use on alternating current comprising an envelope enclosing a lighting space containing rarified gases, two anodes, an electron beam source for emitting electron beams in both half-cycles of said alternating current, 35 which in turn comprises two hot cathodes each enclosed in adjacent recesses of a case, and communicating with the lighting space and the anodes only through openings provided in a body or plasmafilter, said cathodes being separated 40 from the body or plasmafilter by a distance exceeding substantially the length of the mean free path through the gases, said body or plasmafilter having insulating material on its surface exposed to the electron beams and to the lighting space, the 45 openings having lateral dimensions so restricted that the voltage-current characteristic of the lamp is positive and independent of excess electron emission by said cathodes.

50 9. An electric lamp comprising an envelope enclosing a lighting space containing rarified gases, an anode, an electron beam source which in turn comprises an indirectly heated hot cathode heated by a heating body connected with the terminals of the lamp, said heating body being 55 parallel to the path of the discharge current, a body or plasmafilter provided with openings for the passage of the electron beams, said body or plasmafilter separating the cathode from the lighting space and from the anode and having 60 insulating material on its surface exposed to the electron beams and to the lighting space, the openings having lateral dimensions so restricted that the voltage-current characteristic of the lamp is positive and independent of excess electron emission by said cathode.

65 10. An electric lamp for use on alternating current comprising an envelope enclosing a lighting space containing rarified gases, two anodes, an electron beam source for emitting electron 70 beams in both half-cycles of said alternating current which in turn comprises two indirectly heated hot cathodes heated by heating bodies connected in series with each other and to the terminals of the lamp, said heating bodies being 75

parallel to the path of the discharge current, a plurality of bodies or plasmafilters provided with openings for the passage of the electron beams, said bodies or plasmafilters separating the 5 cathodes from the lighting space and from the anodes and having insulating material on their surfaces exposed to the electron beams and to the lighting space, the openings having lateral dimensions so restricted that the voltage-current 10 characteristic of the lamp is positive and independent of excess electron emission by said cathodes.

11. An electric lamp for use on alternating current comprising an envelope enclosing a lighting 15 space containing rarified gases, two anodes, an electron beam source for emitting electron beams in both half-cycles of said alternating current comprising a casing having therein two hot cathodes each enclosed in adjacent recesses of 20 said casing, and communicating with the lighting space only through openings provided in a plurality of bodies or plasmafilters, said bodies or plasmafilters having insulating material on their surfaces exposed to the electron beams and to the 25 lighting space, the openings having lateral dimensions so restricted that the voltage-current characteristic of the lamp is positive and independent of excess electron emission by said cathodes, said anodes communicating with the 30 lighting space through openings in said casing enclosing said cathodes.

12. An electric lamp comprising an envelope enclosing a lighting space containing rarified gases, an anode, an electron beam source which 35 in turn comprises a hot cathode enclosed in a

case and communicating with the lighting space and the anode only through openings provided in a body or plasmafilter, auxiliary means inside said case for starting a discharge, said cathode being separated from the body or plasmafilter by a distance exceeding substantially the length of the mean free path through the gases, said body or plasmafilter having insulating material on its surface exposed to the electron beams and to the lighting space, the openings having lateral dimensions so restricted that the voltage-current characteristic of the lamp is positive and independent of excess electron emission by said cathode. 10

13. An electric lamp for use on alternating current comprising an envelope enclosing a lighting 15 space containing rarified gases, two anodes, an electron beam source for emitting electron beams in both half cycles of said alternating current comprising a casing having therein two hot cathodes each enclosed in adjacent recesses of 20 said casing, and communicating with the lighting space only through openings provided in a plurality of bodies or plasmafilters, said bodies or plasmafilters having insulating material on their surfaces exposed to the electron beams and to the 25 lighting space, said recesses also containing means for starting the discharge, the cathodes being separated from the body or plasmafilter by a distance exceeding substantially the length of the mean free path through the gases, the openings having lateral dimensions so restricted that the lamp is positive and independent of excess 30 electron emission by said cathodes.
